STOKER CONVEYER

Howard P. Anderson, Erie, Pa., assignor to The Standard Stoker Company, Incorporated, a corporation of Delaware

Application December 18, 1934, Serial No. 758,023
Renewed March 3, 1936

4 Claims. (Cl. 198—15)

This invention relates to the conveyers for locomotive stokers or like devices and more particularly appertains to the class of stoker conveyers embodying separable end sections connected by a telescopic intermediate section.

Accordingly, it is the main object of this invention to provide a simplified and more compact intermediate conveyer section than heretofore used consistent with a minimum degradation of the fuel conveyed therethrough.

Other objects reside in the particular shape of parts comprising the intermediate conveyer section and in their relation one with the other and with associated parts of the other conveyer sections.

On the drawings,

Fig. 1 is a central longitudinal vertical section through the rear portion of the locomotive and the forward portion of the tender with the stoker conveyer of the invention shown thereon in elevation;

Fig. 2 is a fragmentary view similar to Fig. 1 but with improved stoker conveyer shown in central vertical longitudinal section;

Fig. 3 is a cross sectional view on line 3—3 of Fig. 2;

Fig. 4 is a cross sectional view on the line 4—4 of Fig. 2; and similarly

Fig. 5 is a cross sectional view on the line 5—5 of Fig. 2.

Referring to these figures, 10 represents the locomotive having a boiler backhead 11 apertured at 12 for the introduction of fuel by the stoker S, and by hand when desired, into the firebox 13. The stoker S extends from beneath the deck 14 of the tender 15 forwardly and upwardly through the locomotive cab deck 16 to the lower portion of the aperture or firing opening 12. Any suitable flexible coupling connection, as at 17, may be employed to tie the tender 15 to the locomotive 10 by the usual connections between the tender underframe 18 and the locomotive underframe 19.

The stoker S is of the type employing a rearward or trough conduit section A rigidly mounted in any well known manner on the tender underframe 18 beneath the deck 14, a forward or riser conduit section B rigidly mounted on the locomotive to the backhead 12 by means of the bracket 20, and an intermediate conduit section C. Within these sections there is mounted a conveyer screw comprising the section 21 rotatably mounted in the trough section A, the section 22 rotatably mounted in the riser conduit section B, and the intermediate section 23 rotatably mounted in the intermediate conduit section C. These screw

sections are universally connected at their adjoining ends by universal joints as at 24 and 25. The forward joint 25 is known in the trade as a double universal joint. It employs the connecting link 25a universally attached at its ends in the jaws 5 22a and 23a of the screw sections 22 and 23, respectively.

In conveying fuel from the tender to the firebox it is desirable to do so with a minimum degradation of the lump fuel and, as will presently appear, the intermediate conveyer section of this invention permits the fuel to be passed therethrough with a minimum of grinding and pulverizing, while at the same time, it is simplified and more compact than similar conveyers of past 15 practice.

As best shown in Figures 1 and 2, the intermediate conduit section C comprises telescopic tubular conduit members 26 and 27. The conduit member 26 carries the spherically shaped vertically split clamps 28 for attachment to the spherical hollow ball 29 carried by the trough section A, the two spherical parts 28 and 29 forming a universal joint connection D between the trough section A and the intermediate conduit 25 section C. Likewise, the conduit member 27 constitutes part of a universal joint connection E with the riser conduit section B. The spherical ball 30 on the forward end of the conduit member 27 rests in a spherical seat 31 at the bottom end 30 of the riser conduit section B and a removable cover 32 shaped to conform with the seat 31 clamped over the upper half of the spherical ball 30 forms with the ball and the seat 31 the universal connection E between the riser conduit section B and the intermediate conduit section C. Bolts 33 secure the cover 32 at its sides to a flange 34 extending laterally from the seat 31. Thus it will be understood the intermediate conduit section C at opposite ends is universally connected 35 to the trough section A and to the riser conduit section B. 40

The longitudinal movement necessary in the conveyer organization is provided by the telescopic relation of the conduit members 26 and 27. The former slidably extends into the latter to a resting point therein over the bottom portion of the spherical ball 30 and over and above the seat 31 whereby the overhanging weight of the conduit member 26 and the screw 23 is supported by the seat 31 of the riser conduit section. This construction prevents any sagging or binding of the conduit members 26 and 27.

In Fig. 1 it will be observed that the universal connection E between the intermediate and riser 55

conduit sections is disposed closely adjacent the cab deck 16 and a portion thereof extends through the deck into the cab 40. It is important therefore to make this joint construction as compact as possible to avoid objectionable intrusion into the cab 40 and at the same time the internal construction of the parts must permit free and loose passage of the fuel. This is accomplished in the construction of this invention by the particular shape and relation of the conduit members 26 and 27. It will be seen from Figures 2, 4, and 5 that the portion of the conduit member 26 within the rear part of the conduit member 27 closely encompasses the screw section 23 to a point rearward of the jaw 23a where the internal floor or round bottom of the conduit member 26 slopes away from the screw and is formed with that portion extending beneath the jaw 23a having a greater internal radius than that portion closely housing the screw. The relation is such that the space between the bottom portion 26a and the jaw 23a is no less than the space between the hub 23b of the screw 23 and the bottom portion 26b of the conduit member 26; and the point where the internal floor begins to slope away from the screw is spaced rearward from the jaw 23a at least a distance equal to the space between the screw hub 23b and the bottom portion 26b. This construction permits the fuel to be conveyed through the intermediate conduit section C and beyond the jaw 23a with a minimum breakdown of the lump fuel. Externally the radius of curvature of the bottom portions 26a, 26b is the same throughout the length of that portion of the conduit member 26 projecting into the conduit member 27.

To provide additional clearance around the double universal joint 25 and the screw jaw 23a the front end portion of the conduit member 26 is cut back as at 35 to a point rearward of the plane of the spherical ball 30 so that there is even more clearance at the sides and top of the jaw 23a than along the bottom. Thus the effective area for the fuel about the jaw 23a and the link 25a is greater than the area for the fuel in the rearward portion of the conduit member 26; and forward of the extreme end of the conduit member 26, as shown in Figures 2 and 5, the internal area of the conduit member 27 and of the lower end of the riser conduit section B is still greater than the area for the fuel in the plane of the jaw 23a and this also facilitates in passing the fuel with a minimum pulverizing or crushing action.

The conduit members 26 and 27 are held from rotating with the screw by the key 36 and the receiving groove 37 and by the lug 38 of the spherical ball 29 fitting in the keyway or groove 39 of the conduit member 26. Rotary motion may be imparted to the screw sections by any suitable drive mechanism.

From the foregoing those familiar particularly with the problems arising out of the use of locomotive stokers will recognize that this invention provides a telescopic intermediate conduit construction of minimum external sizes consistent with and providing for adequate internal areas for free and loose movement of the fuel.

70 I claim:

1. In a stoker conveyer comprising separable end and intermediate conduit sections, the end conduit sections being fixed against longitudinal movement with respect to their supporting structure and the intermediate conduit section includ-

ing telescopic conduit members, the one member having a spherical ball shaped end universally connected to one of the end conduit sections, and the other conduit member comprising a tubular portion at one end slidably resting in said ball shaped end of the first named conduit member and at its other end being universally mounted on the adjacent end of the other end conduit section, and a screw conveyer in each conduit section including a universal joint positioned in the vertical plane of the ball shaped end of the first named conduit member and over that part of said tubular portion of the second named conduit member slidably resting therein, said conduit members being arranged with that portion of the second named conduit member beneath said universal joint of the screw conveyer having a greater radius internally than that portion thereof for the greater distance rearward of said universal joint. 20

2. In a stoker conveyer comprising separable end and intermediate conduit sections, the end conduit sections being fixed against longitudinal movement with respect to their supporting structure and the intermediate conduit section includ- 25 ing telescopic conduit members, the one member having a spherical ball shaped end universally connected to one of the end conduit sections, and the other conduit member comprising a tubular portion at one end slidably resting in said ball shaped end of the first named conduit member and at its other end being universally mounted on the adjacent end of the other end conduit section, and a screw conveyer in each conduit section including a universal joint positioned in the vertical plane of the ball shaped end of the first 30 named conduit member and over that part of said tubular portion of the second named conduit member slidably resting therein, said conduit members being arranged with that portion of the second named conduit member beneath said universal joint of the screw conveyer having a greater radius internally than that portion thereof for the greater distance rearward of said universal joint of the screw conveyer. 35

3. In a stoker conveyer, in combination, a pair of conduit sections, the one conduit section comprising telescopic conduit members, the one telescopic member having a spherical ball-shaped end universally connected to an end of the other conduit section, the other telescopic conduit member comprising a tubular portion at one end slidably resting in said ball-shaped end of the first 50 named telescopic conduit member, and a screw conveyer in each conduit section including a universal joint positioned in the vertical plane of the ball-shaped end of the first named telescopic conduit member and over that part of said tubular portion of the second named telescopic conduit member slidably resting therein, said telescopic conduit members being arranged with that portion of the second named telescopic conduit member beneath said universal joint of the screw 55 conveyer having a greater radius internally than that portion thereof for the greater distance rearward of said universal joint. 60

4. In a stoker conveyer, in combination, a pair of conduit sections, the one conduit section comprising telescopic conduit members, the one telescopic member having a spherical ball-shaped end universally connected to an end of the other conduit section, the other telescopic conduit member comprising a tubular portion at one end slid- 70

ably resting in said ball-shaped end of the first named telescopic conduit member, and a screw conveyer in each conduit section including a universal joint positioned in the vertical plane of the ball-shaped end of the first named telescopic conduit member and over that part of said tubular portion of the second named telescopic conduit member slidably resting therein, said telescopic conduit members being arranged with that

portion of the second named telescopic conduit member beneath said universal joint of the screw conveyer having a greater radius internally than that portion thereof for the greater distance rearward of said universal joint, the sides and top of the second named telescopic conduit member being cut away in the plane of the universal joint of the screw conveyer.

HOWARD P. ANDERSON.
